UNITED STATES PATENT OFFICE.

CLARENCE W. LAKIN, OF HAVERHILL, MASSACHUSETTS.

HEEL FOR SHOES.

1,034,627.

Specification of Letters Patent.

Patented Aug. 6, 1912.

Application filed May 16, 1912. Serial No. 697,593.

To all whom it may concern:

Be it known that I, CLARENCE W. LAKIN, a citizen of the United States, residing at Haverhill, in the county of Essex and State 5 of Massachusetts, have invented an Improvement in Heels for Shoes, of which the following is a specification.

In attaching high heels with certain types of heelng machines, it is customary to attach the heels in two sections, the base portion being first attached to the heel seat of the shoe, and then a top portion being attached to the base portion. These two heel sections, previous to attachment, are highly 15 compressed in a heel compressing machine, and the surfaces of said sections, which are brought together when the second section is attached, are usually very hard and smooth. The result is, that, as there is a strong tend- 20 ency to cause the upper section to slip rearwardly, as the nails are driven to attach it to the lower section, the upper section frequently slips out of place on the lower section, so that it will either not be attached 25 in the desired position, or what is more likely, the attaching nails will be crippled. In either case the heel must be detached and the operation repeated.

The object of my invention is to provide 30 heel sections which are so constructed that they will interlock and rearward slipping of the top section upon the base section will be prevented. I accomplish this object by pro- 35 viding the contacting surfaces of the two sections with transversely extending, inter- locking corrugations in the manner hereafter described and illustrated in the accompany- ing drawing, in which,

Figure 1 is a side elevation of a heel made 40 according to my invention. Figs. 2 and 3 are, respectively, a plan view and a side elevation of the base section. Figs. 4 and 5 are, respectively, a bottom plan view and a side elevation of the top section, and Figs. 45 6 and 7 are detailed views showing different forms of interlocking ribs which I may employ.

According to my invention, the base sec- 45 tion *a*, which is adapted to be attached di-

rectly to the heel seat of the shoe, is corrugated to provide a series of transversely extending ribs *a'*, and the top section *b* is also corrugated on its base surface to provide a series of transversely extending ribs *b'*, which correspond in size and spacing to the 55 ribs *a'* of the base section.

In practice when the base section *a* has been attached, the top section *b* is pressed thereon causing the ribs *b'* to enter the spaces between the ribs *a'*, so that they inter- 60 lock, as illustrated in Fig. 6, with the result that the horizontal force, which would tend to cause the upper section to slip on the lower section, will be resisted to a sufficient extent to prevent such an occurrence under 65 ordinary conditions.

The particular form of ribs which I may employ is not essential as they may be made rounding, as shown in Fig. 6, or sharp, as shown at *a*² in Fig. 7. 70

As the above described ribs on the contacting surfaces are formed during the molding operation, the expense of forming them is practically nothing.

The result which is accomplished would 75 not be accomplished to any appreciable or practical extent, by merely corrugating one of the sections, as the ribs on one section only, would not have any penetrating effect 80 on the highly compressed, smooth surface of the other section, and it is only by the interlocking of the ribs that the desired results are secured.

I claim:—

A heel composed of a base section and a 85 top section having engaging faces, said faces having transversely extending inter-engaging ribs for holding said sections from relative slipping movement longitudinally of the heel, substantially as described. 90

In testimony whereof, I have signed my name to this specification, in the presence of two subscribing witnesses.

CLARENCE W. LAKIN.
